DESIGN FOR A RAIN CAPE

Harvey B. Richards, Lake Bluff, Ill., assignor to
Richards, Boggs and King, Inc., Chicago, Ill., a
corporation of Illinois

Application July 13, 1936, Serial No. 63,821

Term of patent 7 years

To all whom it may concern:

Be it known that I, Harvey B. Richards, a citizen of the United States, residing at Lake Bluff, in the county of Lake and State of Illinois, have invented a new, original, and ornamental Design for a Rain Cape, of which the following is a specification, reference being had to the accompanying drawing, forming a part thereof.

Figure 1 of the drawing is a front view of a rain cape showing my new design; and

Figures 2 and 3 are rear and side perspective views respectively.

The characteristic feature of my design resides in the specific configuration of the hood portion in association with the cape portion of the rain cape, both as shown.

I claim:

The ornamental design for a rain cape substantially as shown and described.

HARVEY B. RICHARDS.
